UNITED STATES PATENT OFFICE.

OTTO A. KNOOPP, OF OAKLAND, CALIFORNIA.

ELECTRICAL INSTRUMENT.

1,171,213

Specification of Letters Patent.

Patented Feb. 8, 1916.

Application filed July 2, 1914. Serial No. 848,636.

To all whom it may concern:

Be it known that I, OTTO A. KNOOPP, a citizen of the United States, residing in Oakland, Alameda county, State of California, have invented certain Improvements in Electrical Instruments, of which the following is a specification.

My invention relates to certain improvements in that type of instrument described and claimed in my Patent No. 1,015,092, dated January 16, 1912, one of the objects of said invention being to provide an instrument of the above noted class which will automatically operate to give indications or records and which, in one form at least, shall be applicable either to alternating or to direct current circuits.

A further object of the invention is to provide an electrical instrument of the above noted type in which the current in the secondary coil or circuit is automatically varied when the primary winding or circuit is energized until the magnetic fields set up by said two windings neutralize each other and in which the amount of current necessary to cause such neutralization is indicated or recorded by a suitable instrument, which may be calibrated in any desired manner.

These objects and other advantageous ends I secure as hereinafter set forth, reference being had to the accompanying drawings, in which,

Figure 1 is a diagrammatic representation of one arrangement of apparatus for carrying out my invention; Fig. 2 is an elevation, partly in section, illustrating certain detail features of the invention; Fig. 3 is a diagrammatic representation of a slightly modified form of my invention; and, Fig. 4 is a diagrammatic view of a special form of apparatus particularly designed for use in measuring direct currents of high potential.

In Figs. 1 and 2 of the above drawings, 1 represents a conductor forming part of a circuit in which the current flow is to be measured, and for the purpose of accomplishing this end, I provide an annular core 2, preferably of laminated iron, having a segmental piece cut out of it so that its two ends are spaced apart a sufficient distance to permit of the introduction of the conductor. Upon the core I mount a winding 3, of suitable length and cross section, and bring its ends out to a pair of terminals 4 and 5. A segmental casing 6 is designed to

fit in and practically fill the space between the spaced ends of the core 2, and in this is mounted a magnetic needle 7 free to swing in the plane of the core 2, though it normally tends to return to or remain in a position radial of said core. On said casing I provide three terminals or binding posts 8^a, 8, and 9, and the first is connected to a contact 10 placed to be engaged by the needle 7 or by a structure movable therewith, whenever it swings in one direction through a predetermined angle from its neutral or normal position. A second contact 11 is placed on the opposite side of the needle 7 in position to be engaged when it swings in the opposite direction, and is connected to the terminal 9. The intermediate contact 8 is electrically connected to the needle 7 or to any contact structure which is movable therewith.

As shown in Fig. 2, the contact 10 is connected through its terminal to one end of an electromagnetic winding 12, while the contact 11 is likewise connected to one end of a second electromagnetic winding 13. In the present instance, these electromagnets are shown as solenoids whose second ends are connected together and electrically connected through a conductor 14 with one end of a body of resistance 15.

In order to normally retain the core 16 of the solenoids in its normal position midway between both of them or in any other predetermined definite position, as well as to return it to such position, I provide a cylinder 19 in which is operative a plunger 20 carried by or connected to the rod 17. This rod also carries between one end of the cylinder and the piston or plunger 20 a spring 21. In this case the magnetic needle 7 is permanently connected through a conductor 22 with one terminal of a battery 23 or other source of direct current whose second terminal is connected to the conductor 14. While one end of the winding 3 of the core 2 is connected to this conductor 22, the opposite end is connected to one terminal of an indicating or recording instrument 24 whose second terminal is electrically connected in any suitable manner to the rod 17 and hence to the contact arm 18 thereof, which is designed to electrically engage any of a number of contacts connected to different parts of the resistance 15. The indicating needle of the instrument shown normally stands in

the middle of its scale and may deflect in either direction. The spring 21 is attached at one end to one end of the cylinder 19 and its opposite end is likewise attached to the piston 20, so that, as above noted, it tends to maintain the core 16 in a position partly within and midway between the solenoids 12 and 13. If, now, the current flows in the conductor 1, there is a magnetic flux set up 5 in the core 2 and the magnetic needle 7 is deflected from its normal position shown in Fig. 1, into engagement with one or the other of the contacts 10 or 11. If it be the former of these contacts which is engaged, 10 the solenoid 12 is energized by current from the source 23 and the core 16 is therefore drawn into this solenoid. As a consequence, the spring 21 is compressed and the resistance arm 18 is so moved that some of 15 the resistance of the bank 15 is cut out of circuit. The current flowing in the circuit formed by the source 23, winding 3, instrument 24 and resistance 15 is, therefore, increased and said winding is so designed that 20 this increased current flow tends to magnetize the core 2 in opposition to the magnetizing effect of the current in the conductor 1, until finally the magnetic flux in said core is reduced to such a point that the 25 magnetic needle disengages the contact 10 and returns to its neutral or mid position. Obviously, the amount of current flowing in the circuit 23, 15, 24, and 3, when this condition exists, is indicated on or recorded by 30 the instrument 24 and bears a definite relation to the current flow in the conductor 1 when the magnetic needle 7 finally disengages the contact 10. The spring 21 will then tend to move the core 16 with its attached parts back to the normal position, but since such movement would at once place 35 additional resistance in circuit with the winding 3, the needle 7 would again be brought into engagement with the contact 40 10, thus again energizing the solenoid 12. Consequently, the solenoid core and the movable element of the instrument 24 are maintained at points whose position varies 45 with the current flow in the conductor 1 and 50 a continuous record or indication is given of such flow if the instrument is properly calibrated.

In that form of my invention shown in Fig. 3, the instrument is shown as designed 55 for use in either an alternating or in a direct current circuit, and in the former case, the line conductors 1^a and 1^b form part of an alternating current circuit. In this case, however, the magnetic needle is replaced by 60 an electromagnetic needle 7^a consisting of a laminated iron core having a winding, one end of which is connected to the line wire 1^b, while the second end is connected through a conductor 27 and a body of variable re- 65 sistance 26 to the line wire 1^a. As before,

the contacts 10 and 11 are respectively connected to the solenoids 12 and 13. In order that the apparatus may be used in direct current circuits, the conductor 22 includes a switch 28 which may be opened to break 70 the circuit, and the direct current source 23 includes in its circuit two other switches 29 and 30 for connecting it to the two ends of the conductor 22 when this is broken by the opening of the switch 28. The winding 3 75 of the core 2, while having one end connected to the instrument 24 as before, has its second end connected to one blade of a double-throw, double-pole switch 31, whereby it may be connected through a conductor 80 32 to the conductor 27 and thence to the line 1^a or on the other hand, may be connected through a conductor 33 and the second blade of switch 31 to the conductor 22. When the switch is so adjusted that the coil 3 is connected to the conductor 32, the conductor 22 is connected through a wire 36 to the line wire 1^b.

If the instrument is to be used for the measurement of direct current, the switch 90 31 is so manipulated that the winding 3 is in circuit with the conductor 22 and at the same time the switch 28 is open while the switches 29 and 30 are closed, while obviously the movable contact member for adjusting the resistance 26 is placed in a position in which the connection with the line 1^a is broken. Under these conditions, the apparatus operates as described in connection with Fig. 1. On the other hand, if it 100 be employed to measure an alternating current flow in the circuit of which the lines 1^a and 1^b form a part, the switch 31 is moved to the position shown in Fig. 3, in which case the winding of the magnetic needle is 105 energized from the lines 1^a and 1^b, while the winding 3 and the parts in connection therewith are likewise connected across said main lines through the resistance 26, conductor 32, switch 31, winding 3, instrument 24, re- 110 sistance 15, conductor 22 and switch 31 to the line 1^b. As before, the magnetic field set up by the current in the conductor 1^b causes a flux in the core 2 and the current in the winding 3 required to neutralize said 115 flux sufficiently to keep the magnetic needle 7^a out of engagement with the contacts 10 and 11, bears a definite ratio to the flow in the line 1^b. The instrument 24 may be calibrated to give direct readings of such flow. 120 When this form of my invention is employed for use on direct current circuits after being used to measure alternating currents, it will be understood that if necessary the needle 7^a may be polarized in any suitable manner so that it will deflect in the proper direction when the core 2 is excited.

It is to be noted that in the form of the invention shown in Fig. 3, the battery or direct current source 23 furnishes the ex. 130

citing current for the winding of the needle 7^a when the apparatus is modified for use in direct current circuits and also furnishes the compensating current for the coil 3.
 5 When the apparatus is used for measuring alternating current, the manipulation of the switch 31 substitutes alternating current from the line for the direct current in the winding 3, it being necessary that the current for excitation and compensating be in phase with the line current. Obviously, therefore, the line current can be used for the above noted purpose when the line circuit is not inductive and for inductive current circuits the secondary alternating current source is to be provided either from a shunt in series with the line or from the secondary of a current transformer whose primary is in series with the line.
 10
 15
 20 In Fig. 4, I have shown the invention as designed for use in measuring direct currents of high potential, and in this case the core 2 has one winding 35 connected between the line conductors through a body of resistance 26^a, with a second or compensating winding 3^a connected as described in the arrangement of Fig. 1. As in the instrument shown in Fig. 3, the magnetic flux produced in the core 2 by the winding 35 or by a conductor 1^b, is automatically neutralized by the operation of the solenoids 12 and 13, one or the other of which acts to vary the amount of the resistance in circuit until such neutralization is completed by reason of the current flowing in the secondary winding 3^a. Since the apparatus is so designed that the solenoid core 16 holds the resistance arm 18 in the proper position to cause the current flow through said winding to remain 35 at or near its neutralizing strength, the instrument 24, being properly calibrated, gives the indication or record of the current flow in the line conductors.
 40
 45

It is to be understood that the casing 6 or other structure carrying the needle 7 and its associated contacts is usually, though not necessarily made to be conveniently removable from the core 2 in order to permit of the introduction and removal of the line conductor in which the current flow is to be measured inside of said core. In the case of Fig. 4 the needle and its coöperating parts may be permanently fixed in place. If desired, the resistance 15 may be formed of a column of carbon plates and the parts so adjusted that the spring 21 normally prevents the arm 18 from compressing said resistance which is therefore so high that the ammeter reads zero. If now the core 2 be slipped over the line 1 so that the flux produced causes the needle 7 to engage the contact 10, the energization of the solenoid 12 causes the resistance to be compressed against the action of the spring 21, permitting a compensating current to flow in the

winding 3 until the effect of the line current is neutralized, when the circuit of said solenoid is broken. As before, the current indicated by the ammeter will bear a definite ratio to that in the line.

70

I claim:—

1. The combination in an electrical instrument of a core; a winding thereon; a movable member actuated by magnetic flux in said core; a contact engaged by said member 75 when it is deflected from a normal position; a current indicating device; a body of resistance; a source of current in circuit with said resistance, the winding and said device; an electromagnet having a movable part and 80 in circuit with the movable member and its contact; and a contact arm connected to the movable part of the electromagnet for varying the amount of resistance in circuit when the movable member engages its contact. 85

2. The combination of a core adapted to be subjected to the influence of a magnetic field; a winding thereon; a source of current; a body of resistance and a current indicating device in circuit with said winding; 90 a member movable under the action of the magnetic flux in said core; a contact engaged by said member when it is deflected; and means in circuit with said member and contact for automatically adjusting the 95 amount of said resistance, when the contact and member are engaged, until the flux in the core is neutralized.

3. The combination of a core adapted to be subjected to the influence of a magnetic 100 field; a winding thereon; a current indicating device and a source of current in the circuit with said winding; a member movable under the action of magnetic flux in the core; a contact engaged by said member when it 105 is deflected; and means in circuit with said contact and member for automatically varying the current flow in the winding, when the member engages the contact, until the flux in the core is neutralized. 110

4. The combination of a core adapted to be subjected to the influence of a magnetic field; a winding thereon; a current indicating device and a source of current in circuit with said winding; a member movable under 115 the action of magnetic flux in the core; a contact engaged by said member when it is deflected; and means in circuit with said contact and member for automatically varying the current flow in the winding to bring 120 the flux in the core to a predetermined value.

5. A current measuring instrument consisting of an annular core having ends spaced apart to permit of the introduction of a current carrying conductor; a device 125 for indicating the presence of flux in said core; a winding for the core; means in circuit with the winding for causing a current flow therein; means for indicating the amount of said current; and means for auto- 130

matically adjusting the flow of current to an amount necessary to bring the flux in the core to a predetermined density.

6. A current measuring instrument consisting of an annular core having ends spaced apart to permit of the introduction of a conductor adapted to set up a flux in said core; a device including a movable member for indicating the presence of a flux 10 in the core; a contact placed to coöperate with said member; means in circuit with the contact and the movable member, for causing a flux in the core opposed to that produced by the conductor within the same; 15 means for indicating the amount of current necessary to produce the opposing flux; and means for automatically adjusting the current flow to an amount necessary to cause the flux to be practically zero.
- 20 7. The combination of a core adapted to be subjected to the influence of a magnetic field; a winding thereon; a current indicating device, a body of resistance and a source of current all connected in circuit with said 25 winding; a movable member mounted adjacent said core; a winding on said member; a contact mounted to be engaged by said member when it is deflected from a normal position by the action of flux in the core 30 upon the winding carried by the movable member; and means in circuit with said latter winding and the contact for automatically adjusting the amount of said resistance in circuit to bring the current in the core 35 winding to an amount necessary to cause the flux in the core to be substantially neutralized.
8. The combination of a core; a winding thereon; a current indicating device, a body 40 of resistance and a source of current all connected in circuit with said winding; a member movable under the action of flux in the core; a contact placed to be engaged by said member when this is deflected; an electro- 45 magnet in circuit with said contact; and means actuated by the movable member of said electro-magnet for varying the amount of resistance in circuit.
9. The combination of a core adapted to 50 be subjected to the influence of a magnetic field; a winding thereon; a current indicating device, a body of resistance and a source

of current all connected in circuit with said winding; a member movable under the action of flux in the core; two contacts 55 mounted to be respectively engaged by the member when it is oppositely deflected by flux in the core; two solenoids respectively in circuit with said contacts and also connected to the movable member; a core acted 60 on by said solenoids; and means operatively connected to the core for automatically adjusting the amount of resistance in the circuit.

10. A current measuring instrument consisting of an annular core having ends spaced apart to permit of the introduction of a current carrying conductor; a winding for the core; means in circuit with the winding for causing a current flow therein; means 70 for indicating the amount of said current; with a device for indicating the presence of flux in said core including a movable member and a winding thereon connected in circuit with a source of current. 75

11. A current measuring instrument consisting of an annular core having ends spaced apart to permit of the introduction of a current carrying conductor; a winding for the core; means in circuit with the 80 winding for causing a current flow therein; a device operatively associated with said means for indicating the amount of said current; a device including a movable member and a winding for indicating the presence of flux in said core; contacts placed on opposite sides of the movable member in positions to be engaged when said member is deflected by flux in the core; two solenoids respectively connected to said contacts 90 and also in circuit with the winding on the movable member; a core for the solenoids; and means actuated by said latter core for adjusting the current flow through the winding to an amount at which the flux in the 95 annular core is neutralized.

In testimony whereof, I have signed my name to this specification, in the presence of two subscribing witnesses.
